UNITED STATES PATENT OFFICE

104,506

DESIGN FOR A BICYCLE HANDLE BAR EXTENSION STEM

Ewald F. Pawsat, Maysville, Ky., assignor to Wald
Manufacturing Company, Incorporated, a cor-
poration of Kentucky

Application January 11, 1937, Serial No. 66,989

Term of patent 14 years

To all whom it may concern:

Be it known that I, Ewald F. Pawsat, a citizen
of the United States, residing at Maysville, in
the county of Mason and State of Kentucky,
have invented a new, original, and ornamental
Design for Bicycle Handle Bar Extension Stems,
of which the following is a specification, refer-
ence being had to the accompanying drawing,
forming a part thereof.

In the drawing:

Figure 1 is a side view of a bicycle handle bar
extension stem showing my new design.

Figure 2 is a front view of the bicycle handle
bar extension stem, a portion being broken away
for convenience in illustration.

Figure 3 is a top view of said stem.

I claim:

The ornamental design for a bicycle handle bar
extension stem, as shown.

EWALD F. PAWSAT.
